UNITED STATES PATENT OFFICE.

LOUIS P. MOOERS, OF CLEVELAND, OHIO, ASSIGNOR, BY MESNE ASSIGNMENTS, TO PEERLESS MOTOR CAR COMPANY, OF CLEVELAND, OHIO, A CORPORATION OF WEST VIRGINIA.

CHANGE-SPEED GEARING.

SPECIFICATION forming part of Letters Patent No. 737,442, dated August 25, 1903.

Application filed June 16, 1902. Serial No. 111,804. (No model.)

To all whom it may concern:

Be it known that I, LOUIS P. MOOERS, a citizen of the United States, residing at Cleveland, in the county of Cuyahoga and State of Ohio, have invented a certain new and useful Improvement in Change-Speed Gearing, of which the following is a full, clear, and exact description, reference being had to the accompanying drawings.

My invention relates to improvements in change-speed gearing especially applicable for use on automobiles which are driven by engines or motors which drive in only one direction and at approximately one speed.

The invention consists in the novel features of construction hereinafter described, reference being had to the accompanying drawings, which illustrate one form which I have contemplated embodying in my invention, and said invention is fully disclosed in the following description and claims.

The object of my invention is to provide mechanism whereby one shaft may be driven from a driving-shaft either backward or at different speed forward at the will of the operator.

Referring to the drawings, Figure 1 is a top plan view of the lower section of the casing of my device, showing the gears and other parts in cross-section. Fig. 2 is a sectional plan view taken below the shafting and gearing, showing the operating mechanism. Fig. 3 represents a section on the line 3 3 of Fig. 2 looking to the right. Fig. 4 is a section on the line 4 4, Fig. 1, looking to the left. Fig. 5 is a detail view of the reversing-pinion shaft-shifter; and Fig. 6 is an enlarged view of one of the gears, and it illustrates one probably necessary structural characteristic of all of the gears.

In carrying out the above objects I employ a casing composed of the two parts A A', having suitable openings in the ends thereof for supporting the bearing-boxes a a' a² a³, which are held in place by the caps a⁴ a⁵ and the rings a⁶ a⁷.

In a bearing-box a' is mounted the end of the main driving-shaft B, having rigidly secured thereto a small pinion b and having

in its inner end an axial cavity b', which is 50 adapted to receive a bushing b².

Mounted in the alined bearing a³ is the shaft C, this being the shaft which the mechanism shown is designed to drive backward or forward at various speeds. This shaft has the 55 squared portion c and the cylindrical end c', which is rotatively mounted in the bushing b². Slidably mounted upon the squared portion c is a sleeve D, provided at one end with a spur-gear d and at the other end with the 60 internal clutch-teeth and external spur-gear teeth d². The internal clutch-teeth of the gear d² are adapted to engage and fit upon the small pinion b.

Mounted in the bearing-boxes a a² is a counter-shaft E, provided with the squared portion e. A small pinion e² and a gear-wheel e³ are rigidly secured to the shaft, and between the gear e³ and the bearing a, upon the squared portion e, is slidably mounted the sleeve F, 70 carrying a gear-wheel f' and having a circumferential groove f². The squared portion e is so located with respect to the shaft E that when the sleeve F abuts against the small pinion e² the gear-wheel f' will mesh with the 75 small pinion b. The sleeve F is moved into and out of this position by means of a fork f⁷, which engages in its circumferential groove f² and is slidably mounted at its lower end upon the pin f⁸, secured to the lug f⁹ and to the 80 casing. This fork is moved to and normally held against the lug f⁹, at which time the gear f' and pinion b are in engagement by means of a spring f¹⁰. An operating-arm f¹¹ is rigidly secured to said fork f⁷, for a purpose which 85 will hereinafter be described.

Located in the casing in a suitable position with respect to the sleeve D is the sliding shifting-rod G, having rigidly secured thereto a fork g, which engages in the circumferential groove d' in said sleeve and serves as a means for shifting the sleeve D and the gears carried thereby. A collar g² is rigidly secured to the shifting-rod g and has projecting therefrom a lug g³, so placed that it will engage the 90 operating-arm f¹¹, and thereby shift the fork f⁷, and consequently the sleeve F and its gear f', which is thereby disengaged from gear b.

The collar g^2 , with its lug g^3 , is arranged upon the shifting-rod G , so that the teeth of the gear d^2 will be brought into complete engagement with the teeth of the gear e^3 before the 5 lug g^3 engages the operating-arm f^{11} , and so also that the gear f' will be entirely disengaged from the pinion b before the internal clutch-teeth of gear d^2 engages said pinion.

A shaft H is secured to one end of the casing and to a lug a^5 therein, and on this shaft a broad pinion h is rotatably mounted. This pinion has a hub h' , in which is a circumferential groove h^2 . A lever P is pivoted to the casing below the pinion h . At one end of 15 this lever is a pair of jaws $p^2 p^3$, one of said jaws p^3 being longer than the other. The other end of said lever is connected to a slide having at one end an upwardly-extended fork p^6 , which engages the groove h^2 and is designed to shift the broad pinion h . A spring Q acts to hold the slide in the position shown, although it is moved into that position by the action of pin g^4 on the lever P . The lever P is so located that its long jaw p^3 will lie in 25 the path of the pin g^4 when the pinion h is out of engagement with the other gears.

The device is manipulated in the following manner: If it is desired to retain the shaft C at rest, the sleeve D , with its gears, is left in 30 the position shown in Fig. 1, with the gear d out of engagement with the pinion e^2 and the external gear d^2 out of engagement with the gear e^3 and also with the internal clutch-teeth of the gear d^2 out of engagement with the 35 pinion b . Should it be desired to obtain a medium speed, the sleeve D is moved so that the teeth of the gear d^2 will engage the gear e^3 . Highspeed is obtained by shifting the rod G still farther in the same direction, and 40 thereby carrying the gear d^2 along until the lug g^3 engages the arm f^{11} , thereby unlocking the gear f' from the pinion b and then bringing the internal clutch-teeth of the gear d^2 into engagement with the pinion b . When it is desired to drive the shaft C forward at slow 45 speed, the shifting-rod G is moved in the contrary direction until the fork g shifts the sleeve D and carries the gear-wheel d into engagement with the small pinion e^2 . To reverse the motion of the driven shaft, the shifting-rod G is moved still farther in the same direction until the gear d passes out of mesh 50 with the pinion e^2 , whereupon the lug g^4 engages the jaw p^3 of the lever P , thereby rocking the same and causing it, by means of the slide p^4 (shown in Fig. 5) and the fork p^6 , to move the broad pinion h' into engagement with the pinion e^2 and the gear d , which moves toward it. The movements of the different 55 parts when in the position just described will be thus: Motion is conveyed from the pinion b through the gear f' to the shaft E , from thence by the pinion e^2 to the broad pinion h' and to the gear-wheel d , which drives the shaft C . This, by reason of the different 60 movements of the gears, will convey a reverse movement to the driven shaft C . When the 65

shifting-rod G is moved again in the opposite direction to disengage the reversing mechanism, the lug g^4 engages the arm p^3 , thereby rocking the lever and positively moving the broad pinion h out of engagement with the pinion e^2 . It must be borne in mind that these parts may be interchanged and varied according to the desire of the mechanic without departing 75 from the spirit of this invention.

In order to facilitate the engagement of the several gears as stated, it is probably necessary that the end of the several teeth be tapered and the end of the interdental spaces 80 flaring, which construction is illustrated in Fig. 5.

Having described my invention, I claim—

1. In a change-speed gearing, the combination of a main driving-shaft, an external gear 85 secured to it, a driven shaft mounted in axial alinement therewith, a member slidably mounted on the driven shaft and having internal clutch-teeth adapted to take over said external gear on said driving-shaft, whereby 90 it may operate to make a clutch with said gear, a counter-shaft and gears thereon adapted to mesh with said external gear on the main shaft, means for moving the gear on the counter-shaft out of engagement with the 95 gear on the main shaft, means for moving said clutch member on said driven shaft into engagement with the gear on the main shaft, and means for communicating rotation from the gear on the counter-shaft to the driven 100 shaft, substantially as described.

2. In a change-speed gearing the combination with a main driving-shaft, of a gear secured to it, a driven shaft mounted in axial alinement therewith, and a parallel counter-shaft, three gears mounted on said counter-shaft, one being for engagement with the gear on the driving-shaft, a member provided with internal clutch-teeth and two external gears and movable endwise only upon the driven 110 shaft, said two external gears being adapted for engagement with two of the gears on the counter-shaft, and said member provided with internal clutch-teeth being for engagement with the gear on the driving-shaft, and mechanism 115 for moving said three gears, substantially as described.

3. In change-speed gearing, the combination with a driving-shaft of a gear secured to it, a driven shaft mounted in axial alinement therewith, a parallel counter-shaft and an endwise-movable reversing-gear mounted on a parallel axis, with three gears secured to the counter-shaft, a movable member provided with internal clutch-teeth and two external 125 gears movable endwise only upon the driven shaft, and mechanism for moving said gears and also for moving the reversing-gear, substantially as described.

4. In a change-speed gearing, the combination with the main driving-shaft and driven shaft, of a counter-shaft, suitable gears slidably mounted upon said driven shaft, means whereby said gears are adapted to rotate with 130

5 said driven shaft, means whereby said gears may be shifted into different positions, a gear-wheel slidably mounted upon said counter-shaft adapted to rotate the same, means whereby said gear may be thrown into and out of operation with the main driving-shaft, a gear rigidly mounted upon said counter-shaft, a pinion also rigidly mounted on the counter-shaft, a second counter-shaft, a pinion mounted thereon adapted to reverse the motion of said driven shaft, means whereby said gears upon said driven shaft may be thrown into operation with said pinion upon said counter-shaft, and said gear-wheel on 10 said counter-shaft, and means whereby said gear loose on said first-mentioned counter-shaft may be thrown out of operation, and said driven shaft operated in direct connection with the main driving-shaft, substantially as described.

5. In a change-speed gearing, the combination with the main driving-shaft of a small pinion, a driven shaft, suitable gears slidably mounted endwise only on said driven shaft for operating the same, a counter-shaft, a gear slidably mounted endwise only and adapted normally to be retained in engagement with the pinion on said main driving-shaft, a fixed gear upon said counter-shaft, a 25 fixed pinion upon said counter-shaft, said gear upon said counter-shaft being adapted to mesh with a sliding gear upon the driven shaft, and said fixed pinion upon the counter-shaft being adapted to mesh with another gear on the driven shaft a second counter-shaft, a pinion loosely mounted upon the same adapted to be brought into engagement with the fixed pinion upon said first-mentioned counter-shaft, and mesh with one of 30 said gears upon the driven shaft when the fixed pinion upon said counter-shaft and said gear on said driven shaft are out of engagement, and means for shifting all of said gears, substantially as described.

45 6. In a change-speed gearing, the combination with the main driving-shaft of a pinion, and a driven shaft, of a counter-shaft, gears slidably mounted endwise only on said driven shaft and adapted to rotate the same, a gear 50 slidably mounted endwise only on said counter-shaft and adapted to rotate the same, a shifting-fork controlling the movement of said gear and normally retaining the same in engagement with the pinion upon said main driving-shaft, an operating-arm secured to 55

said gear-operating fork, a fixed gear and a pinion upon said counter-shaft, a second counter-shaft, a broad pinion loosely mounted upon said second counter-shaft, an operating-fork for said broad pinion adapted to 60 normally retain said pinion in an extreme position, an operating-lever for the operating-fork of said broad pinion, a shifting-rod, a fixed fork upon said shifting-rod adapted to shift the gears upon said driven shaft, a lug 65 provided on said shaft for tripping said operating-arm of said gear upon said first-mentioned counter-shaft, and a second lug provided upon said rod for engaging said operating-lever of said broad pinion, substantially 70 as described.

7. In a change-speed gearing, the combination with the casing and main driving-shaft of a pinion, mounted in said casing, a driven shaft also mounted in said casing and having gears slidably mounted endwise only on said shaft and a shank having its bearing in the end of said main driving-shaft, one of said gears having internal clutch-teeth, the internal clutch-teeth being adapted to engage 80 the pinion on the main driving-shaft, a counter-shaft rotatably mounted in said casing, a gear loosely mounted upon said counter-shaft and adapted to slide into and out of mesh with the gear on the driving-shaft, a gear 85 upon said counter-shaft, a fixed pinion upon said counter-shaft, a fork operating said gear loosely mounted upon said counter-shaft and normally retaining the same in engagement with the pinion upon the main driving-shaft, 90 a coiled spring insuring this position, an operating-arm secured to said fork, a second counter-shaft rigidly mounted in the casing, a broad pinion loosely mounted upon said 95 rigid counter-shaft, a lever mounted in said casing, a link carried by said lever, a fork carried by said link for operating said broad pinion, jaws upon said lever, a shifting-rod entering said casing, a fixed fork upon said rod for operating the slidably-mounted gears 100 upon said counter-shaft, and a lug for engaging the jaws of said lever thereby operating the same, substantially as described.

In testimony whereof I hereunto affix my signature in the presence of two witnesses. 105

LOUIS P. MOOERS.
